Primary Examiner — Joseph Kukella*Assistant Examiner* — Heather Wenc(74) *Attorney, Agent, or Firm* — Walter J. Tencza, Jr.(57) **CLAIM**

The ornamental design for the human figure and tray apparatus as shown and described.

DESCRIPTION

FIG. 1 is a left side, top, and front perspective view of the human figure and tray apparatus, in accordance with the present invention;

FIG. 2 is a front elevational view of the human figure and tray apparatus;

FIG. 3 is a rear elevational view of the human figure and tray apparatus;

FIG. 4 is a left side elevational view of the human figure and tray apparatus;

FIG. 5 is a right side elevational view of the human figure and tray apparatus;

FIG. 6 is a top plan view of the human figure and tray apparatus; and,

FIG. 7 is a bottom plan view of the human figure and tray apparatus.
